UNITED STATES PATENT OFFICE.

JENS M. JENSEN, OF RACINE, WISCONSIN.

RADIATOR CONSTRUCTION.

Application filed April 29, 1920. Serial No. 377,524.

To all whom it may concern:

Be it known that I, JENS M. JENSEN, a citizen of the United States, and resident of Racine, in the county of Racine and State of Wisconsin, have invented new and useful Improvements in Radiator Constructions, of which the following is a description, reference being had to the accompanying drawings, which are a part of this specification.

The present invention relates to certain new and useful improvements in radiator constructions of that type particularly adapted for use upon tractors, automobiles and similar engine driven vehicles, and which may also be employed with other classes of machinery or apparatus, where it is desirable to cool liquids or fluids by providing a means for increased radiation of heat.

This invention has for one of its objects to provide a novel and simple construction of radiator including a plurality of vertically trending water passageways separated by transversely extending air passageways, the air passageways having means positioned therein whereby the air passing therethrough will be given a tortuous movement to cause the same to engage against the walls forming the water passageways.

A further object of this invention is to provide a plurality of substantially vertically trending water passageways provided with transverse corrugations therein forming transverse air passageways with the adjacent corrugations and having inserts therein provided with projections struck therefrom to form deflecting surfaces in the air passageways for imparting a tortuous movement to the air as it passes therethrough.

With the above and other objects in view, which will appear as the description proceeds, my invention resides in the novel construction, combination and arrangement of parts substantially as hereinafter described and more particularly defined by the appended claim, it being understood that such changes in the precise embodiment of the herein disclosed invention may be made as come within the scope of the claim.

In the accompanying drawing I have illustrated one complete example of the physical embodiment of my invention constructed according to the best mode I have so

far devised for the practical application of the principles thereof, and in which:

Fig. 1 is a front view of a portion of a radiator construction embodying my invention,

60

Fig. 2 is a view part in section and part in elevation taken on the plane indicated by the line 2—2 of Fig. 1, and

Fig. 3 is a fragmentary perspective view of a portion of one of the vertically trending water passageways and air passageway inserts.

Referring now more particularly to the drawing, the numeral 5 indicates a radiator having an upper water compartment or tank 6, a lower water compartment (not shown), and a plurality of substantially vertically trending water tubes 7 forming fluid passageways connecting the upper and lower water compartments.

The water tubes 7 are provided with horizontal or transverse corrugations 8 and are positioned as depicted in Fig. 1 with the opposite corrugations of adjacent water tubes forming substantially transverse air passageways 9. Each adjacent pair of tubes 7 have secured therebetween an insert or plate 10 which plate has projections or ears 11 alternately struck from opposite sides thereof and so inclined as to provide a plurality of deflecting surfaces positioned within each air passageway 9.

When the projections 11 are struck from the inserts, an opening 12 is formed which permits the air to readily pass from one side of the inserts to the other. As will be readily apparent to those skilled in the art to which an invention of this character appertains, the air passing into the passageways 9 is deflected by the projections 11 and thrown by centrifugal force against the walls of the tube 7, then passes on in eddying currents, which eddying movement of the air is maintained by the following projections 11.

The inserts 10 not only serve to cause the air to travel in eddying currents, but also provide an extra cooling fin for absorbing the heat from the water.

What I claim as my invention is:

105

A radiator comprising a plurality of pairs of nested water tubes formed with lateral projections which are so arranged that the projections of one tube of each pair co-operate with those of the other tube so that

110

a plurality of air passageways therebetween are provided, and a plate interposed between the tubes of each pair, said plate having alternately disposed fins struck 5 therefrom thereby providing a plurality of openings in said plate through which the air currents may pass, said fins being alternately inclined with respect to the vertical,

whereby the respective air currents are directed upwardly and downwardly as they ¹⁰ pass from one side of the plate through the openings therein to the other side of the plate.

In testimony whereof, I affix my signature.

JENS M. JENSEN.
